JUG

William E. Fillmore, Toledo, Ohio, assignor to Owens-Illinois Glass Company, Toledo, Ohio, a corporation of Ohio

Filed May 31, 1962, Ser. No. 70,351

Term of patent 14 years

(Cl. D58—5)

FIG. 1

The characteristic features of my design reside in the portion shown in full lines and in the particularly shaped handle in combination with the configuration of the upper portion of the jug, all as shown.

I claim:

The ornamental design for a jug, substantially as shown and described.
